W. A. GRIMES.

NEWSPAPER BINDER.

APPLICATION FILED MAY 24, 1920.

1,412,078.

Patented Apr. 11, 1922.

UNITED STATES PATENT OFFICE.

WILLIAM A. GRIMES, OF RICHMOND, INDIANA.

NEWSPAPER BINDER.

1,412,078.

Specification of Letters Patent. Patented Apr. 11, 1922.

Application filed May 24, 1920. Serial No. 383,766.

To all whom it may concern:

Be it known that I, WILLIAM A. GRIMES, a citizen of the United States, residing in the city of Richmond, in the county of Wayne, State of Indiana, have invented a new and useful Newspaper Binder, of which the following is a full, clear, and comprehensive specification and exposition, the same being such as will enable others to make and use the same with exactitude.

The object of my present invention, broadly stated, is to provide a newspaper binder which is light in weight, comparatively small in size, positive in its results, easily operated and controlled, quickly and easily attached and detached to and from a newspaper, and which can be manufactured and sold at a comparatively low price.

The particular object in view is the provision of a device for securing together the various sheets of a newspaper or the like whereby the various pages will be retained intact and whereby the leaves may be turned in the same manner as a book or magazine, at the same time enabling one to retain the paper in extended condition when held in one's hands.

It is also to be understood that the device is applicable for temporarily binding together various kinds of papers and legal documents, and for retaining blank sheets of paper in tablet form, and for various other purposes to which it is applicable.

Other objects and advantages of my invention will be brought out in the course of the following description, and that which is new will be correlated in the appended claim.

The preferred means for carrying out the purposes of my invention in a practical manner is shown in the accompanying drawings, in which—

Figure 1 is a side elevation of my device. Figure 2 is a face side elevation showing the mouth open ready to receive a paper. Figure 3 is also a face side elevation, but showing the mouth closed, that is with the lips clamped together. Figure 4 shows the device as clamped upon the upper portion of a newspaper. Figure 5 shows the device as clamped upon the central portion of a newspaper. Figure 6 is a cross section of the main portion or body of the device, as taken on the line 6—6 of Fig. 2. Figure 7 is a face side view of one of the clamps. Figure 8 is an end elevation of one of the clamps.

And Figure 9 is an end elevation of the body portion.

Similar indexes denote like parts throughout the several views.

In order that the construction, the operation, and the advantages of my invention may be fully understood and appreciated I will now take up a detailed description of my invention, in which I will set forth the same as fully and as comprehensively as I may.

Referring now to the drawings in detail: The body of my device is formed from a single piece of very thin but highly resilient sheet metal, and it comprises the two sides 1 and 2, which are disposed at acute angles with relation to each other. Said sides are integrally united by the curved outer central portion 3.

Extending centerward from the edges of the sides 1 and 2 are the jaw members 4 and 5, which extend toward each other. Extending centerward and rearward, with each other, from the edges of the jaw members 4 and 5 are the respective lip members 6 and 7. At the rear edges of the members 6 and 7 the material is doubled upon itself forming the auxiliary lip members 8 and 9, respectively. From the forward edges of the members 8 and 9 the material is bent at right-angles and into contact with the jaw members 4 and 5 thereby forming the respective auxiliary jaw members 10 and 11. At the junctures of the member 10 with the side 1 the material is turned inward at an acute angle both to the member 1 and to the member 10, thereby providing the fin 12. Likewise at the junctures of the member 11 with the side 2 the material is turned inward at an acute angle both to the member 2 and to the member 11, thereby providing the fin 13.

All of said parts are formed of a single piece of material, and are therefore integral with each other, the thickness of which is shown exaggerated in Fig. 6, in order to show the parts more clearly, and in practice the central portion 3 acts as a spring hinge, while the doubling of the jaws and the lips, and the interposition of the fins, renders said portion comparatively stiff and less liable to bend laterally. Said description refers particularly to the central portion of the body. Starting, for instance, half way between the center and the ends of the body above described the jaw mem-

bers 4 and 5 decrease in width to a vanishing point at the extreme ends of the body, and as the lips 6 and 7 are retained parallel with each other and the same distance apart throughout the length of the body, therefore the sides 1 and 2 become offset inward forming the shoulders 14 and 15 and thereby forming the wedge-shaped inclines 16 and 17 which are brought practically into contact with the respective lips 6 and 7.

Two clamp members are provided for each body member, each clamp comprising a curved central portion 18 to surround the parts 1, 2 and 3 at the ends of the body, and having inturned offsets 19 and 20 to engage the shoulders 14 and 15, and having terminal flanges 21 and 22 to contact with the inclines 16 and 17, respectively.

At the extreme ends of the body the material forming the lips 6 and 7, and the inclines 16 and 17, is turned out at right-angles forming the stops 23 and 24 for the clamps to engage with as hereinafter explained.

In practice the clamps should be slid outward in contact with the stops 23 and 24, which will permit the lips to be spaced apart as in Fig. 2, whereby the inner edges of a newspaper A may be placed between the lips, after which the clamps are to be slid toward each other as in Fig. 3 which manifestly will force the lips toward each other and into clamping condition with the paper.

The device may be attached to any part of the inner edge of the newspaper, preferably on the upper half as in Fig. 4, or in the center as in Fig. 5, or it may be attached to the lower half, or a device may be employed on the upper half and another clamp on the lower half.

When the device is attached it is evident that it may be grasped with one's left-hand, thereby enabling one to hold the paper in proper condition for reading, and enabling one to turn the leaves as with a book, and also preventing the leaves from becoming separated and retaining them in consecutive order as long as desired.

When one desires to remove the device it is only necessary to slide the clamp mem-

bers outward to their limits, which of course will release the paper.

I desire that it be understood that various changes may be made in the details of construction and the shape of the various parts without departing from the spirit of the invention and without sacrificing any of the advantages thereof.

Having now fully shown and described my invention, what I claim and desire to secure by Letters Patent of the United States, is—

A newspaper binder comprising in combination a body formed of very thin and highly resilient sheet metal, the same being substantially U-shaped in cross section forming sides which are disposed at acute angles with relation to each other and each terminating in a jaw member which extend toward each other, lip members extending centerward and rearward from the edges of the jaw members, auxiliary lip members formed at the rear edges of the lip members by doubling the material upon itself, auxiliary jaw members formed by bending the material at right-angles, at the forward edges, into contact with the jaw members, fins formed by turning the material inward at right angles, means whereby the jaw members are tapered to a vanishing point at the extreme ends of the body while the lips are retained parallel with each other and of the same thickness throughout, stops formed at the extreme ends of the body, all of said parts being formed of a single piece of material; and a clamp for each end portion of the body, each clamp comprising a curved portion and having inturned offset portions and terminal flanges whereby the clamps will fit on the body and are slidable thereon for opening and closing the lips, all substantially as shown and described, and for the purposes set forth.

In testimony whereof I have hereunto subscribed my name in the presence of two subscribing witnesses.

WILLIAM A. GRIMES.
